TWIN SPRINKLER

Walter Van E. Thompson, Los Angeles, Calif., assignor to Thermson Manufacturing Company, Los Angeles, Calif., a corporation of California

Application January 21, 1935, Serial No. 2,646

1 Claim. (Cl. 299—56)

My invention relates to improvements employed in surface irrigation, and relates particularly to a sprinkler of this character having a unique base and securing means.

5 The ordinary sprinkler, such as is employed for the sprinkling of lawns, comprises a metal body adapted to be secured to the end of a garden hose, such body having a water passage and a discharge orifice from which the sprinkler spray 10 issues. Difficulty is often experienced in getting the sprinkler to lie flat upon the lawn owing to a twist or torsion in the hose. Also difficulty is at times encountered where the sprinkler is placed on a sloping lawn. My present invention 15 comprehends a sprinkler having a simple means adapted for use in several different ways to hold the sprinkler in a desired position of operation.

It is an object of the invention to provide a 15 sprinkler having a body with a leg member pivotally secured thereto, which leg member is sharpened so that it may be driven into the ground as a spike, together with means which will hold the sprinkler body in any one of a number of positions in which said body may be rotated on the leg which is driven into the ground or sod of a lawn. In the preferred practice of 20 my invention I provide a base of substantially triangular form with a hose connection at one corner of the approximate triangle and with legs pivotally secured at the two remaining corners in such a manner that these legs may be employed in forwardly extending relation to serve as an extension of the base of the sprinkler, or 25 may be swung into downwardly projecting position so as to engage the soil as spikes, or may be swung into retracted position against the end-face of the sprinkler body.

A further object of the invention is to provide 30 a sprinkler body having pivotally secured legs of this character adapted to hold the sprinkler body at an angle to the surface of the soil, thereby making it possible to secure the sprinkler in a level position on a sloping lawn, or in angular 35 position on a level lawn for the purpose of controlling the distribution of the spray of water delivered by the sprinkler.

Further objects and advantages of my invention 40 will be brought out in the following part of the specification.

Referring to the drawing which is for illustrative 45 purposes only.

Fig. 1 is a side view of a preferred embodiment 50 of the invention showing the legs in forwardly extending position.

Fig. 2 is a plan view corresponding to Fig. 1.

Fig. 3 is a side elevation showing the legs projecting downwardly and penetrating the soil as spikes.

Fig. 4 is a front elevation showing the manner 5 in which the legs may be employed to hold the sprinkler in tilted relation to the surface of the soil.

Fig. 5 is a fragmentary section taken as indicated on the line 5—5 of Fig. 2. 10

As shown in Figs. 1 and 2 of the drawing, I employ a body 10 which may be cast to the desired form by use of die casting methods. This body forms a pair of circular chambers 11 in side-by-side relation each having a central upwardly faced discharge orifice 12. Extending rearwardly on the line of division A—A between the chambers 11, the body includes an internally threaded hose connection 13 which communicates through a passage 14 with the interior 15 spaces of the chambers 11 indicated by dotted lines 15.

The body approximately coincides in shape with a triangle 16, the hose connection 13 occupying the rearward corner 17 thereof. The 20 body 10 has a pair of lugs 18 projecting forwardly and outwardly therefrom in such position as to occupy the forward corners 20 of the triangle 16. These lugs have the purpose of pivotally securing legs 21 to the body 10 in such a manner 25 that these legs may be swung from the forward position in which they are shown in Figs. 1 and 2 through the downward extending intermediate position indicated in Fig. 3 to the retracted position in which they are shown by dotted lines 22 30 in Figs. 1 and 2.

In the preferred form of the invention each leg 35 comprises a metal bar 23 which may be readily punched from sheet metal, in the configuration shown in Fig. 5 this bar having the forward end 35 thereof pointed as indicated at 24 so that each leg 21 will be equipped with a point whereby it may be driven into the soil, as shown in Figs. 3 and 4. It is further shown in Fig. 5 that the rearward end 25 of each bar 23 has a downwardly extending enlargement 26 in which a relatively large opening 27 is punched. In addition to this, the rearward end 25 of each bar 23 is formed with a rearwardly presented end-face 28 extending perpendicularly to the upper edge 29 of the bar 23 and meeting the upper edge 29 so as to form a corner 31 which will serve as a stop for the bar 23 when it is swung into forward and outward extended position, as shown in Fig. 5 and 45 also in Figs. 1 and 2. 50

Each lug 18 is cast integrally with the body 10 and is cast with its cooperating leg 21 in place in extended position. In the casting of the lug 18, the metal thereof flows around opposite side faces 5 of the enlargement at the rearward end 25 so as to form side walls 32 and 33. The metal also passes through the opening 27 and forms therein a metal hinge pin 34 joining the side walls 32 and 33. I have found that the lugs may be cast in 10 position on the ends of the legs 21 without a bond being formed between the metal of the legs and of the lugs. Exceptionally good results may be obtained where the legs 21 are made of iron or steel and the body 10 and the lugs 18 are cast 15 from a metal having a relatively low-temperature melting point, such, for example, as tin or an alloy thereof. The metal in being cast flows into engagement with the rearward end-face 28 of the leg 21 so as to form a wall 35 which will abut 20 the end-face 28 when the leg 21 is in forwardly extended position. Therefore, the legs 21 may not be swung upwardly from the positions in which they are shown in Figs. 1, 2, and 5, but may be rotated downwardly in view of the fact that the 25 lower portion of the enlargement 26 is made semi-circular as clearly shown in Fig. 5.

A suitable recess is formed in the lower face of the body 10 to receive the legs 21 when they are in retracted position, as shown in Fig. 1, by projecting the lugs downwardly relative to the plane 30 of the lower face 37 of the body 10, thus making it possible to form the hinge pin 34 in such lowered relation to the lower face 37 that the legs 21 will lie substantially flat against this lower face 37 when they are folded under the sprinkler body 10.

It will be noted that the hinge means represented by the lugs 18 are so formed that the legs 21 swing through vertical planes which diverge 40 forwardly and outwardly from the body 10. Therefore when the legs 21 are in forwardly extended position, as best shown in Fig. 2, they define an extension of the base or body of the sprinkler. These extended legs 21 in fact define 45 an enlarged base for the sprinkler having the form of a triangle indicated by dotted lines 38. By the use of the legs 21 the base of the sprinkler may be extended not only forwardly but laterally as well, owing to the fact that the vertical planes 50 through which the legs swing diverge forwardly and outwardly, as clearly shown. A further advantage of this manner of hingedly mounting the legs 21 is that when they are swung downward and rearward into retracted position, they will lie 55 entirely within the projected area of the body 10, as clearly indicated by dotted lines 22 of Fig. 2.

If a user finds that the hose has very little twist or torque therein when the sprinkler is placed upon the lawn, he may merely extend the

legs 21 so as to increase the size of the sprinkler base to that of the triangle 38 shown in Fig. 2, whereupon the sprinkler will lie flat upon the surface of the lawn. Should the hose have a considerable twist therein, he may, without rearranging the hose so as to more or less eliminate this twist, extend the legs 21 downward into the position indicated at 40 in Fig. 3 and push them into the sod or soil, whereupon the sprinkler will be firmly held in place. A further advantage of 10 the use of the legs in the position shown at 40 in Fig. 3 is that the sprinkler is held with sufficient security to resist displacement as a result of inadvertent kicking of the hose by a person walking across the same. 15

As shown in Fig. 4, the legs 21 may be employed to adjust the angle of the sprinkler relative to the surface of the ground if it is displaced. Each leg when projected downwardly serves as a spike 20 which is pivotally secured to the sprinkler body and on which spike the body may be rotated within prescribed limits. By raising or lowering one of the vertical legs while the other is left substantially stationary it is possible to adjustably rotate the sprinkler body into a desired 25 angular position relative to the surface of the lawn on which the sprinkler is placed. In this way the spray delivered by the sprinkler may be directed in one direction or another, or may be kept level even though the lawn on which the 30 sprinkler is placed may be non-horizontal.

Although my invention is shown in a simple practicable form, it is recognized that various changes may be made therein by the substitution of recognized equivalents without departing from 35 the spirit of the invention; therefore, the invention is to be limited in scope only by the herein-after set forth claim.

I claim as my invention:

In a sprinkler of the character described, 40 the combination of: a body having a pair of side-by-side chambers having outlets, and having an inlet for supplying liquid to said chambers; supporting formations on said body projecting downwardly therefrom and resting at the corners of a 45 triangular area; a pair of leg members so pivotally connected to two of said supporting formations that they are swingable from an extended position horizontally outward from said body in diverging relationship to provide a larger base, 50 into depending position for penetration into the ground, and into collapsed position below said body and within the confines of said formations; and stop means operative when said leg members 55 are in extended position for holding them in positions for coengagement by said leg members and said formations with the ground.

WALTER VAN E. THOMPSON.
